INVENTOR:

Joseph A. Eno,
BY Draker & Co., ATTY'S.

UNITED STATES PATENT OFFICE.

JOSEPH A. ENO, OF NEWARK, NEW JERSEY.

STEAM-GENERATOR.

SPECIFICATION forming part of Letters Patent No. 424,103, dated March 25, 1890.

Application filed May 15, 1889. Serial No. 310,851. (No model.)

To all whom it may concern:

Be it known that I, JOSEPH A. ENO, a citizen of the United States, residing at Newark, in the county of Essex and State of New Jersey, have invented certain new and useful Improvements in Steam-Generators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to certain improvements in that class of steam-generators illustrated or represented by the one shown in my prior application for a patent filed October 15, 1888, and serially numbered 288,170, the 20 object of my present improvement being to reduce the cost of construction and to allow the grates to be more easily and quickly changed or removed for repair.

The invention consists in the arrangements 25 and combinations of parts, substantially as will be hereinafter set forth, and finally embodied in the claims.

Referring to the accompanying drawings, in which like letters indicate corresponding 30 parts in each of the figures, Figure 1 is a front elevation of a portion of a steam-boiler, more especially of the marine type, having fire-chambers extending horizontally through the water-chamber. Fig. 2 is a similar elevation 35 showing a modified construction. Fig. 3 is a plan of a portion of a system of steam-generating pipes adapted to be arranged in said fire-chamber; and Fig. 4 is a detail section of a certain part of said system, taken on line x , 40 Fig. 2.

In said drawings, a indicates a portion of an ordinary boiler having the horizontal fire-chamber b therein, around which is formed a water-chamber in the ordinary way. Within 45 said chamber b is arranged a system of water-conducting and steam-generating pipes, which form a cage, and may, after suitable uncoupling at the front of the boiler, be removed together from the fire-chamber for repair or 50 other purposes, substantially as described in my prior application. The said cage consists, more particularly and preferably, of two pipes

$c c$, arranged longitudinally at the bottom of the chamber b , a similar pipe d , arranged in like manner at the top of said chamber and connecting pipes $e e$, conforming more or less closely to the concaved walls f of the said fire-chamber, the said connection-pipe being arranged in series extending up from the pipes $c c$ and entering into opposite sides of the pipe d .

In the prior case above referred to I described and in specific clauses claimed the pipes when the said pipes formed a water-grate. In the present case I employ a cage in 65 which the pipes do not extend across the lower part of the chambers b and form a water-grate, but an independent and separable grate is employed having its opposite bearings on raised shoulders or bearings $g g$ on or of the cage, whereby the said grate may be removed or separated from the cage without disturbing the longitudinal or connecting pipes. Said shoulders may be formed of the pipes $c c$, as in Fig. 1; or when a single pipe or false bottom c' —such as is shown in Fig. 2—is employed the said false bottom may be suitably formed to provide an ash-pit c'' , of adequate capacity, and to properly receive the ends of the grate-bars and hold them in the desired 80 position, the said shoulders then being formed at or toward the sides of said false bottom.

Inlet-pipes $h h$ are provided at the forward end of the pipes $c c$ to supply the latter with water from the boiler, and the pipe i serves to 85 convey the heated water to the upper portion of the water-chamber of the said boiler.

To reduce the cost of construction and to secure a more perfect and durable joint, I have formed the pipe d substantially as shown 90 in Figs. 3 and 4, in which the said pipe is shown to be provided with flanges $k k$ at the sides, into which or to which the pipes e may be inserted or secured at right angles to said pipe d , as indicated in Fig. 3. The interior 95 of the said flanges of the pipe is provided with passages $l l l$, which are formed to cause the water as it flows upward to change its course and flow forward or toward the pipe i , thus facilitating the flow of the water and insuring a perfect circulation. By connecting the pipes e to the pipe d in the manner described and forming the passages l in a direction greater or less than a right angle to the

pipe *d*, or inclining said passages *l* to the passage in the pipe *d*, so that the water will be directed forward, I am enabled to secure a more perfect joint and to reduce the cost of 5 construction materially and secure a more perfect circulation.

When I employ the single pipe or false bottom *c*, I may provide a hand-hole *m*, which may be closed in any suitable manner.

10 Having thus described my invention, what I claim as new is—

15 1. The improved steam-generator herein described, combining, with a boiler, a cage consisting of longitudinal and connecting pipes for conducting water through the fire-chamber of said boiler from and to the water-chamber of said boiler, and a grate arranged within said cage and separable from said longitudinal and connecting pipes, whereby said grate 20 may be removed from the boiler fire-chamber without disturbing the water-pipes of said cage, substantially as and for the purposes set forth.

25 2. In a steam-generator, substantially as described, the combination, with a boiler *a*, having a fire-chamber *b* therein, of a cage consisting of pipes *c c*, arranged longitudinally at the bottom of said chamber, a similar pipe *d*, arranged at the top of said chamber, connecting- 30 pipes *e e*, extending upward from said pipes *c c* to the pipe *d*, inlet-pipes *h h*, supplying the

pipes *c c*, a pipe *i*, to connect the pipe *d* with the upper part of the water-chamber, and a separable grate supported by said pipes *c* and forming an ash-pit at the lower part of the 35 fire-chamber, substantially as and for the purpose set forth.

3. The improved steam-generator, substantially as described, combining with the boiler having a pipe or pipes *c* in the fire-chamber 40 thereof a series of pipes *e e*, a longitudinal pipe *d*, receiving said pipes *e e* at right angles and having passages *l l* therein inclined to the central passage so as to direct the water forward, a supply-pipe, and a pipe *i*, connecting with the water-chamber of the boiler, 45 substantially as and for the purposes set forth.

4. The improved steam-generator, combining with suitable inlet and outlet pipes and longitudinal pipes *c* or *c'* a flanged pipe *d*, 50 having inclined passages *l l*, and connecting-pipes *e e*, joined to said flanged pipe at right angles thereto, substantially as and for the purposes set forth.

In testimony that I claim the foregoing I 55 have hereunto set my hand this 10th day of May, 1889.

JOSEPH A. ENO.
